Maier & Neustadt, P.C.

[73] Assignee: **Mitsubishi Denki Kabushiki Kaisha**, Tokyo, Japan

[57] CLAIM

[**] Term: 14 Years

The ornamental design for battery for computer, as shown and described.

[21] Appl. No.: 29/082,215

DESCRIPTION

[22] Filed: Jan. 16, 1998

FIG. 1 is a front elevational view of battery for computer embodying our new design;

[30] Foreign Application Priority Data

FIG. 2 is a rear elevational view thereof;

Jul. 18, 1997 [JP] Japan 9-62104

FIG. 3 is a left side elevational view thereof;

[51] LOC (6) Cl. 13-02

FIG. 4 is a right side elevational view thereof;

[52] U.S. Cl. D13/103

FIG. 5 is a top plan view thereof;

[58] Field of Search D13/103; 439/96-100,
439/163, 176; 361/683

FIG. 6 is a bottom plan view thereof;

[56] References Cited

FIG. 7 is a cross-sectional view thereof taken along line 7—7 in FIG. 1;

U.S. PATENT DOCUMENTS

FIG. 8 is a top, front and right side perspective view thereof; and,

D. 356,992 4/1995 Dilgard D13/103
5,019,465 5/1991 Herron et al. 429/97
5,225,293 7/1993 Mitchell et al. 429/97

FIG. 9 is a top, front and left side perspective view thereof showing the battery for computer when in use.

The computer shown in phantom lines in FIG. 9 is for illustrative purposes only and forms no part of the claimed invention.
